UNITED STATES PATENT OFFICE

101,384

DESIGN FOR A TRAILER OR SIMILAR ARTICLE

Estok Menton, Detroit, Mich.

Application August 5, 1936, Serial No. 64,264

Term of patent 7 years

To all whom it may concern:

Be it known that I, Estok Menton, a citizen of the United States of America and residing at Detroit, in the county of Wayne and State of Michigan, have invented a new, original, and ornamental Design for a Trailer or Similar Article, of which the following is a specification, reference being made to the accompanying drawing, forming part thereof.

Fig. 1 is a side elevational view of a trailer showing a new design.

Fig. 2 is a perspective view thereof.

Fig. 3 is a front elevational view thereof.

The side of the trailer opposite the side seen in Fig. 1, is the same as the side seen in Fig. 1, except that there is no door on opposite side.

I claim:

The ornamental design for a trailer or similar article substantially as shown and described.

ESTOK MENTON.
